CLAIM

We claim the ornamental design for an injection device add-on, as shown and described.

DESCRIPTION

FIG. 1 is a right side view of an injection device add-on.

FIG. 2 is a top view of the design of FIG. 1.

FIG. 3 is a front view of the design of FIG. 1.

FIG. 4 is a bottom view of the design of FIG. 1.

FIG. 5 is a left side view of the design of FIG. 1.

FIG. 6 is a rear view of the design of FIG. 1.

FIG. 7 is an isometric and top view of the design of FIG. 1; and,

FIG. 8 is a view similar to FIG. 7 of the design of FIG. 1, additionally showing (in broken lines) the injection device environment of the design.

The broken lines in FIGS. 2, 4, 7 and 8 depict portions of the article or of the injection device environment of the article that form no part of the claimed design. The radiating dash-dot lines in FIGS. 1-3 and 5-8 represent illumination,
